UNITED STATES PATENT OFFICE.

LYSLE H. NUTTER, OF HAMBURG, ARKANSAS.

DISPLAY CABINET.

Application filed October 4, 1922. Serial No. 592,370.

To all whom it may concern:

Be it known that I, LYSLE H. NUTTER, a citizen of the United States, residing at Hamburg, in the county of Ashley and State of Arkansas, have invented certain new and useful Improvements in Display Cabinets, of which the following is a specification, reference being had to the accompanying drawings.

10 This invention relates to display cabinets, and has for its object to provide a cabinet capable of holding a number of articles of merchandise not only for the purpose of display, but for the purpose of permitting the merchandise to be measured and cut in an economical manner.

15 It is another object of the invention to provide a cabinet of this character adapted to hold spools of material, and wherein means are provided for preventing the material from unwinding to a greater extent than that desired.

20 It is a further object of the invention to provide a cabinet of this character having means for supporting a number of spools of material, and also means whereby the material from any one of the spools may be measured and cut without leaving any long projecting ends of material after the material 25 desired has been removed.

25 With these and other objects in view, the invention consists in the improved construction and arrangement of parts to be herein-after more particularly described, fully 30 claimed and illustrated in the accompanying drawings, in which:—

35 Figure 1 is a top plan view of a display cabinet constructed in accordance with an embodiment of the invention;

40 Figure 2 is a rear elevation; Figure 3 is a transverse sectional view; and

45 Figure 4 is a fragmentary sectional view of the partition and the supports of the shafts.

50 Referring to the drawings, 5 designates a cabinet including end walls 6 and 7, a front wall 8, a rear wall 9 and a bottom 10. A cover or lid 11 is provided in the form of a frame having a pane of glass disposed therein. The cover is hinged to the edge of the rear wall 9. The upper edges of the end walls 6 and 7 incline toward the front wall 8 so as to dispose the lid 11 in an in-

clined position and thus permit the contents 55 of the cabinet to be viewed from above.

Disposed within the cabinet is a partition 12 having a threaded socket member 13 disposed in each side face thereof and centrally of the partition. The partition divides the 60 cabinet into two compartments. The end walls 6 and 7 are each provided with openings 14, through which a shaft 15 extends, one shaft being provided for each compartment. The end portion 16 of each shaft is 65 threaded and adapted to engage the adjacent threaded socket of the partition 12. The end portion 17 of the shaft is flattened to provide a thumb piece for rotating the shaft to apply or remove the same from the 70 casing. Each of the shafts 15 are intended to receive a number of spools or reels A of merchandise, such as ribbon, elastic, braid, lace, etc. The front wall 8 is provided with an elongated opening 18 in which a pane of 75 glass 19 is disposed so that the merchandise within the cabinet may be viewed from the front thereof.

The rear wall 9 of the casing is provided with a slot 20 which extends longitudinally 80 of the rear wall, adjacent the upper edge thereof. This slot is intended to receive the ends of the material carried by the reels or spools A so that the material may be removed from the reels according to the 85 quantity required by the customer. A tightener 21 is provided, said tightener comprising a rod having its end portions extended at right angles and provided with openings 22, said end portions being adapt-

90 ed to embrace the ends of the rear wall and to receive pivot means 23. The tightener is mounted so that the major portion thereof is disposed substantially in front of the slot to prevent the material on the 95 spools or reels from unwinding to a greater extent than that required. This eliminates the necessity of winding the material back upon the reels after a portion thereof has been removed. Of course, if it is desired 100 that a large quantity be removed from the spools and that the spool be rotated rapidly, the tightener may be moved upwardly and the material disengaged therefrom.

105 In connection with the cabinet, novel measuring means are used, said means comprising a supporting member 24 which is secured to the lower edge of the outer face

- of the rear wall. This supporting member is intended to support a rule 25, the length of the rule corresponding to the length of the casing so as to eliminate projections at the end walls of the casing when the device is not in use. The rule 25 is provided with a slot 26 which extends longitudinally of the rule and through the side faces thereof. A stop member 27, such as a screw or pin, is disposed centrally of the rear wall 9 and within the slot 26, said pin being adapted to engage either end portion of the slot 26 to prevent disengagement of the rule from the casing.
- 15 In the use of the device, as previously stated, a number of spools or reels are placed upon the shafts 15. The ends of the material on the spools are then threaded through the slots 20. When it is desired 20 to remove material from a spool in the left hand compartment of the cabinet, say for instance a spool adjacent the partition 12, the rule 26 is moved longitudinally of the rear wall of the cabinet, upon the support 25 24, until the inch indication on the rule comes beneath the projecting end portion of the material. This eliminates the necessity of unwinding a large portion of the material in order to permit the same to be measured.
- 30 The material may then be measured in the usual manner and when the desired quantity has been removed the material is cut at the end of the rule disposed adjacent the stop so that only a very small end portion is left 35 projecting from the rear wall of the casing. This eliminates the necessity of raising the cover and rewinding the material on the reel. This operation may be repeated for a spool in the left hand compartment of the cabinet, as it is possible to move the rule

so that the inch indication thereof will come immediately beneath the projecting end of the desired material.

From the foregoing it will be readily seen that this invention provides a novel form of display cabinet which may be constructed in a compact form and which in addition to protecting the material and preventing shop wear, provides means for dispensing the material without unnecessary labor and without causing waste. In addition to this it provides means whereby the material may be displayed at all times. All of these features are possessed by a device which is simple in construction.

55 What is claimed is:

A display cabinet comprising a casing, a shaft disposed in said casing and adapted to support merchandise, the rear wall of said casing having a longitudinally extending slot, for the reception of the merchandise, a supporting member carried by the lower portion of the rear wall exteriorly of the casing, a rule movably mounted on the support, said rule being movable longitudinally of the rear wall of the casing, said rule being provided with a longitudinally disposed slot extending substantially the entire length thereof, and a stop member extending outwardly from the rear wall of the casing and extending through the slot of the rule, said stop member being positioned above and at substantially the longitudinal center of the supporting member, said stop member coacting with the ends of the slot to limit the longitudinal movement of the rule in either direction.

60 65 70 75 In testimony whereof I hereunto affix my signature.

LYSLE H. NUTTER,
